SECURITY DOOR-POST

Gerson Snyder, Philadelphia, Pa., assignor to Snyder Manufacturing Company, Philadelphia, Pa., a corporation of Pennsylvania

Filed Aug. 11, 1969, Ser. No. 18,645

Term of patent 7 years

Int. Cl. D8—03

U.S. Cl. D8—203

FIG. 4.

FIG. 1 is a perspective view of a security door-post embodying the design of the present invention;

FIG. 2 is a reduced side elevational view thereof;

FIG. 3 is a rear elevational view thereof; and

FIG. 4 is an enlarged bottom plan view taken along line 4—4 of FIG. 2.

I claim:

The ornamental design for a security door-post, substantially as shown and described.
